UNITED STATES PATENT OFFICE.

ERNEST GREIL AND EMILE AUDIGER, OF PARIS, FRANCE, ASSIGNEES TO
THE ELECTRIC LIGHTING BOARDS, LIMITED, OF LONDON, ENGLAND.

ELECTRIC CONTACT OR CURRENT-TAKING DEVICE.

SPECIFICATION forming part of Letters Patent No. 663,750, dated December 11, 1900.

Application filed January 10, 1900. Serial No. 979. (No model.)

To all whom it may concern:

Be it known that we, ERNEST GREIL and
EMILE AUDIGER, electricians, citizens of the
Republic of France, and residents of 138 Faubourg
St. Honoré, Paris, France, have invented
certain Improvements in or Relating to
Electric Contacts or Current-Taking Devices,
of which the following is a specification.

This invention relates to electric contacts
or current-taking devices for electric applica-
10 nances, and more especially those intended for
illuminating purposes.

If we consider, for example, the case of ap-
pliances of the form of candlesticks or can-
delabra placed upon a table, it has hitherto
been necessary with the means usually em-
ployed for taking the electric current to con-
duct to the foot of the appliance a small cable,
which is frequently the cause of much incon-
20 venience, as it encumbers the piece of furni-
ture upon which the appliance rests and ren-
ders this latter liable to be upset. Our in-
vention serves to obviate this defect. In ac-
cordance therewith we connect the electric
25 conductor not with the illuminating device,
but with the piece of furniture itself, and we
adapt in one or more positions upon such piece
of furniture contacts or current-taking de-
vices in accordance with our invention. We
30 will now describe the said current-taking de-
vice, which possesses the advantage of not
presenting either a projection or a cavity when
arranged in position.

In the accompanying drawings, Figure 1
35 represents in cross-section and in plan a por-
tion of a table upon which is mounted the
fixed part of our device. Fig. 2 shows in sec-
tion and in external elevation the intermediate
40 movable part, which is arranged between
the said fixed part and a third piece which
forms part of the illuminating device. Fig.
3 represents the third part in plan and in sec-
tion. Fig. 4 shows in section the whole of the
45 various parts when the appliance is arranged
in an operative condition. Fig. 5 represents
a table arranged in accordance with our in-
vention having adjacent conducting masses
in parallel strips or bands. Fig. 6 represents
50 a table with superposed conducting masses.
Fig. 7 shows in section a current-taking de-

vice intended to be employed with superposed
conducting masses.

The fixed part, Fig. 1, rigidly attached to
the table or other piece of furniture, consists
of a block *a* of insulating material—such as
55 wood, ebône, or the like—in which are em-
bedded two conducting pieces or masses *b b*,
constituted, in the manner of the brushes em-
ployed in electrical apparatus, by means of a
large number of metallic wires arranged in
60 juxtaposition. This block is embedded in
the piece of furniture in such a manner as to
be flush with the upper surface thereof, as
are also the masses or conducting pieces *b b*.
These latter are connected by their lower por-
65 tions at *c c* with the electric conductors by
means of flexible wires. The piece thus con-
stituted is and remains embedded in the piece
of furniture and may be concealed by a cloth
or cover placed upon this latter. In the
70 two masses or brushes *b b* two points *d d*,
which are rigidly connected with a small cyl-
inder *e*, of insulating material, are adapted
to enter. One of these points is in metallic
connection with a strip of metal *f*, arranged
75 at the bottom of a cavity *g*, formed in the
base of the cylinder opposite to that in which
the points are situated. The other point
communicates with a band of metal *h*, ar-
ranged upon the cylindrical surface of the
80 block. When this cylinder is placed upon
the block *a*, the said points *d d* being engaged
in the brushes, it projects from the table, and
it is upon it that the base of the appliance is
engaged. In this base is fitted the part which
85 forms the third piece of our device above re-
ferred to. This latter is formed of a block *i*,
comprising a recess supplied with a metallic
partition *j* and in which the cylinder *e* may
be maintained by friction. At the bottom of
90 this recess is provided a projecting metallic
part *k*, one portion of which, *l*, is adapted to
enter within the other and is acted upon by
a spring. The metal partition *j* is in com-
munication by means of a conductor with one
95 of the poles of the lamp, while the said pro-
jecting metallic part *k* is connected with the
other pole.

When it is desired to render the apparatus
operative, the cylinder *e* is placed upon the
100

fixed part *a*, the points *d d* being engaged in the metallic masses *b b*. Then upon this cylinder is engaged the foot of the apparatus provided with the part *i*, in whose recess the cylinder is adapted to enter, as already explained.

The current passes from the masses *b b* to the points *d d*, and from these latter it passes, on the one hand, to the partition *j* along a band *h* and, on the other hand, to the projecting metallic part *k* by way of the metallic part *f* and then proceeds to the lamp through the conductors of the apparatus. This method entirely obviates the necessity for the presence of conducting-wires upon the furniture, and to all appearance the illuminating appliance is merely placed thereon. Of course several such devices may be provided upon the same piece of furniture for the purpose 20 of enabling several appliances to be arranged upon it or of enabling the position of the said appliances to be changed.

We would point out that we do not in any way confine ourselves to the device described. 25 For example, we may make the masses *b b* of various shapes. Thus, for instance, they may consist of two parallel bands of a certain length, of two concentric circles, &c., thus enabling the appliance to be arranged 30 upon any point in the length of the bands or concentric circles. It should be remarked that in certain cases the points *d d* may form part of the lamp-base itself.

A table arranged in such a manner as to 35 permit of a lamp or the like being placed upon any point of the same has formed in its surface grooves, within which are lodged metallic cubes *b* or else bands of conducting metal, as above stated. Upon the surface of 40 the table thus provided are arranged a sheet of asbestos *m* and a sheet of india-rubber *n*. The connections with the cables or bands *b* are effected in any suitable manner. It will 45 of course be understood that at the extremities of the table the section of the conducting-bands are covered with an insulating-sheet. We are thus able to arrange the conducting masses *b b* in the form of superposed bands or sheets separated by an insulating-layer *o*, Fig. 6. In this case the points *d d* 50 would be of unequal lengths, and the longer point should be covered by an insulating-sheath *p* at that portion of it which is in the thickness of the first conducting-sheet. This 55 arrangement may be applied to partitions, floors, or the like, and covers may be made which may merely be placed upon the table if it is desired that this latter should remain intact.

60 We would point out that the points *d d* might be adapted directly to the base of the incandescent lamp which it is desired to place in circuit and form an integral portion of its socket, as this might be advantageous under 65 certain conditions—for example, in order to rapidly form a luminous sign.

Our invention is also applicable to the es-

tablishment of luminous letters or signs, especially for advertising purposes. We also reserve the right to constitute the metallic 70 masses intended for the reception of the points in various manners, enabling electrical communication with the points and their penetration. They may consist of metallic wires, thin metal sheets, lead shot, sheet-tin, plum-bago, &c. The points need not necessarily be fixed to a separate part *e*, but may be adapted directly to the appliance. In certain cases this would constitute a simplification of the 75 device.

In certain circumstances the invention may be simplified by mounting the lamp directly upon a socket which is rigidly connected with a suitable part. This extremely simple arrangement may be useful in certain applications of our invention where decorative effect 85 is not an object.

What we claim, and desire to secure by Letters Patent of the United States, is—

1. The combination of a plurality of electric parallel conducting-bands laid in the grooves of a table or other support and connected alternately to the positive and negative poles of an electric generator, an insulating-block, a pair of conducting projections 95 secured thereto and each of which is adapted to penetrate one of the contacts, and a separate contact-plate suitably connected to each of said projections.

2. The combination with a plurality of electric contacts connected respectively with the positive and negative poles of an electric generator, and mounted in a table or other suitable support, of an insulating-block having conducting projections thereon adapted 105 to penetrate the bands, contact-plates connected respectively to said projections and mounted on separated portions of said block, a socket-piece in the base of a translating device adapted to receive said block and contacts on said socket-piece adapted to engage 110 said plates and connected to the conductors leading to said translating device.

3. The combination with a plurality of electric contacts connected respectively with the positive and negative poles of an electric generator, and mounted in a table or other suitable support, of an insulating-block having conducting projections thereon adapted 115 to penetrate said contacts, contact-plates, one embracing said block and the other seated in a recess in the upper end thereof, a socket-piece in the base of a translating device adapted to receive said block, an annular contact on said socket-piece connected with 120 one of the conductors leading to said translating device and adapted to engage the contact-plate embracing said block, and a yieldingly-mounted contact on said socket-piece connected with the other conductor leading 125 to said translating device and adapted to engage the contact-plate seated in the recess in said block.

4. The combination with a plurality of elec-

tric contacts connected respectively with the positive and negative poles of an electric generator, mounted one above the other in a table or other support and separated by a layer of insulating material, and a layer of easily-penetrable insulating material on the top of said table or support above said contacts, of a circuit-closing device having projections thereon terminating at different levels, and adapted to be inserted through said layer of penetrable insulating material to respectively

engage said contacts, and insulating material on one of said projections, as and for the purpose set forth.

In testimony whereof we have signed our names to this specification in the presence of two subscribing witnesses.

ERNEST GREIL.
EMILE AUDIGER.
